CRUDE OIL PURIFIER

Gonzalo Meneses Castellanos, Placetas, Cuba, assignee to Meneses y Compania, Placetas, Las Villas, Cuba

Application June 26, 1945, Serial No. 601,664
In Cuba May 4, 1944

7 Claims. (Cl. 210—150.6)

1

The present invention relates to new and useful improvements in purifiers for crude oil used as a fuel in industrial apparatus, such as the fire boxes of locomotive boilers, stationary boilers and other steam generating power plants, and the invention has for its primary object to provide means for separating and eliminating sediment, extraneous burned-out material and condensation water which may be found mixed with the oil and recovering the crude oil that is free of such impurities, whereby to improve the efficiency and to promote economy in the operation of the steam boiler.

It is well known that sediment, burned-out material and condensation water contained in crude oil does not permit proper combustion and entail intermittent flame, lowering of pressure, imperfect flue connection, vibration of the sheets and generally unsatisfactory conditions in the fire box. Sediment and sludge in the feed tubes do not allow the proper circulation of oil and interfere with the proper functioning of the atomizing burner of the boiler and produces carbon scale on the burner tip which thus impairs efficiency in producing heat and also requires frequent and costly repairs.

It is further necessary to maintain a uniform temperature for the oil so that it may have the proper viscosity for proper combustion as well as for properly feeding the oil to the burner, and it is accordingly an object of the present invention to overcome such unsatisfactory and objectionable conditions by regulating the temperature and purifying the oil before the same is fed to the burner.

A further object of the invention is to provide an apparatus of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view.

Figure 2 is an end elevational view.

Figure 3 is a longitudinal sectional view.

Figure 4 is a transverse sectional view.

Referring now to the drawings in detail, where in for the purpose of illustration I have disclosed a preferred embodiment of the invention, the crude oil purifier consists of upper and lower cy-

2

lindrical members 5 and 6 supported in a horizontal position one above the other by connecting plates 7 at the ends of the members.

The ends of the cylinder 5 are closed by end plates 8 and 9, while the ends of the cylinder 6 are closed by end plates 10 and 11.

A transverse partition 12 is provided in the cylinder 5 separating the same into compartments 13 and 14.

15 A valve 15 provides a connection between the compartment 13 of the upper cylinder 5 and the lower cylinder 6 while a similar valve 16 provides connection between the compartment 14 and the lower cylinder. A baffle 17 is provided in the upper portion of the cylinder 6 between the valves 15 and 16.

16 A crude oil intake pipe 18 is attached to the end plate 9 of the upper cylinder 5 leading from a suitable source of supply or storage tank and a 20 discharge pipe 19 communicates with the compartment 13 by way of the opposite end plate 8. A temperature indicator or thermometer 20 is attached to the discharge pipe 19.

25 The side of the partition 12 in the chamber 13 is formed with a lug 21 received in a recess 22 in one end of a cylindrical strainer 23, the other end of the strainer communicating with the discharge pipe 19, as shown to advantage in Figure 3 of the drawings.

30 A steam heating coil 24 is supported in the lower portion of the lower cylinder 6 by means of brackets 25, the coil being connected to a steam supply pipe 26 on the outside of the cylinder leading from a steam boiler (not shown) for supplying steam under pressure to the coil.

35 A branch pipe 27 is also connected to the pipe 26 and communicates with the chamber 13 through a tubular nipple 28 which extends through one side of the upper cylinder 5. A conventional form of manually operated valve 29 is provided in the pipe 27.

40 The end of the coil 24 remote from the steam pipe 26 is provided with a pet cock 29 to drain water condensed in the coil 24. A steam valve 50 in the pipe 26 regulates the flow of steam to the coil 24.

45 A branch pipe 30 is also connected to the steam pipe 26 leading into the side of the lower cylinder 6 and provided with a valve 31 for the admission of steam for flushing out the cylinder 6 and the lower portion of the cylinder 6 is provided with a drain 32 having a valve 33 therein.

50 A branch pipe 34 is also connected to the pipe 27 and communicates with the chamber 14

55

through the side of the cylinder 5, and is likewise provided with a control valve 35.

A by-pass pipe 36 connects the chambers 13 and 14 and is also provided with a control valve 37.

To the end plate 10 of the lower cylinder 6 is attached a water gauge 38 to indicate the level of liquid in the cylinder 6, the upper and lower ends of the gauge being connected to the cylinder by means of tubes 51 having screens 39 formed on the ends thereof.

In the operation of the device, crude oil from the supply tank enters the chamber 14 by way of the intake pipe 18 and passes downwardly through the valve 16 into the lower cylinder 6. The oil then passes under the baffle 17 and is heated by the steam coil 24 and then passes upwardly into the chamber 13 by way of the valve 15. Thereafter, the oil passes through the strainer 23 and out of the chamber 13 to the oil burner, not shown, by way of the supply pipe 19. At this time, the steam valve 50 is opened to supply steam to the heating coil 24, but the bypass control valve 37 and the remaining steam valves 31, 28 and 35 are closed, as is the pet cock 29 and drain valve 33.

To clean out the lower cylinder 6, fuel valves 15 and 16 are closed, and the by-pass valve 37 of the line 36 is open to provide communication between the upper chambers 14 and 13 to prevent a vacuum from forming in the fuel line. Valve 28 and valve 35 are closed, pet cock 29 is closed, drain valve 33 is open, and blow-out valve 31 for the lower cylinder 6 is open. The valve 50 for the heating coil 24 may be opened or closed as desired. When it is desired to blow out the chamber 13 of the upper cylinder 5, the fuel valve 16 is closed, but the fuel valve 15 is left open. If there is a valve in the line 19 to the burner, such valve, not shown, is closed also. The valve 37 is closed, as is the valve 35, and the valve 31. The drain or blowout valve 33 is open, as is the valve 28, whereby steam pressure is admitted to the upper chamber 13 to blow out the same through the valve 15, lower chamber 6, and drain valve 33. This operation will also serve to at least partially clean the filter or strainer 23. If it is desired to blow out the fuel line 19 and the burner, not shown, the fuel valve 15 is closed in addition, and the strainer 23 in fuel line 19, as well as the burner, are blown out by pressure of steam entering through the valve 28.

When it is desired to shut down the device and assuming the above operations have been performed, the steam valve 50 for the coil 24 is closed, and the coil drained by the pet cock 29. With bypass control valve 37 and steam valves 31 and 28 closed, steam valve 35 is opened, whereby to supply steam under pressure to the upper cylinder 14 which is operative to force surplus oil in such chamber 14 out of the chamber and back to the fuel tank, not shown, through the supply conduit 18.

To start up the device, the fuel line 19 and burner, not shown, are blown out, as stated above. Thereafter, the fuel valves 15 and 16 are opened and steam is supplied to the coil 24 by opening the valve 50. All the remaining steam valves 28, 35 and 31 and bypass control valve 37 are closed, as are the pet cock 29 and drain valve 33.

When the device is shut down, and if it is desired to preheat the fuel or oil in the supply tank, the valve 35 may be left open, whereby steam

passes through the chamber 14 and supply pipe 18 to the fuel tank, not shown, whereby to heat the fuel in the tank.

It is believed the details of construction, manner of operation and advantages of the apparatus will be readily understood from the foregoing without further detailed explanation.

While I have herein disclosed a preferred embodiment of the invention, it is to be understood that various changes in construction may be resorted to without departing from the spirit of the invention or the appended claims.

Having thus described the invention, what is claimed is:

1. An oil purifier, comprising upper and lower horizontally-disposed cylinders, a substantially vertical partition in said upper cylinder and separating the same into a pair of chambers, separate means including valves connecting said

chambers to said lower cylinder, an oil intake conduit opening into one of said chambers, an oil outlet pipe opening out of said other of said chambers, a filter in operative association with said outlet pipe for filtering oil entering the same, a filter being in said last-named chamber, a by-pass pipe connecting said chambers, a valve in said last-named pipe, and means in said lower cylinder for heating oil therein.

2. An oil purifier, comprising upper and lower

horizontally-disposed cylinders, a substantially vertical partition in said upper cylinder separating the same into a pair of chambers, separate means including separate valves connecting said chambers to said lower cylinder, an oil intake pipe connected to one of said chambers, an oil outlet pipe connected to the other of said chambers, a filter in operative association with said outlet pipe for filtering oil entering the same, said filter being in said last-named chamber, a

coil in said lower cylinder, said coil having connections to receive a fluid-heating medium, branch connections leading from said connections to said lower cylinder and to each of said chambers, valves in each of said branch connections whereby to selectively supply a fluid-heating medium to said lower cylinder and to each of said chambers, a by-pass pipe connecting said chambers, and a valve in said last-named pipe.

3. An oil purifier, comprising upper and lower horizontally-disposed cylinders, a substantially vertical partition in said upper cylinder separating the same into a pair of chambers, separate means including separate valves connecting said chambers to said lower cylinder, an oil intake

pipe connected to one of said chambers, an oil outlet pipe connected to the other of said chambers, a filter in operative association with said outlet pipe for filtering oil entering the same, said filter being in said last-named chamber, a coil in said lower cylinder, said coil having connections to receive steam, branch connections leading from said connections to said lower cylinder and to each of said chambers, valves in each of said branch connections whereby to selectively supply steam to said lower cylinder and to each of said chambers, a by-pass pipe connecting said chambers, and a valve in said last-named pipe.

4. An oil purifier, comprising upper and lower horizontally-disposed cylinders, a substantially vertical partition in said upper cylinder separating the same into a pair of chambers, separate means including separate valves connecting said chambers to said lower cylinder, an oil intake pipe connected to one of said chambers, an oil

70
75

outlet pipe connected to the other of said chambers, a filter in operative association with said outlet pipe for filtering oil entering the same, said filter being in said last-named chamber, a coil in said lower cylinder, said coil having connections to receive steam, branch connections leading from said connections to said lower cylinder and to each of said chambers, valves in each of said branch connections whereby to selectively supply steam to said lower cylinder and to each of said chambers, a by-pass pipe connecting said chambers, a valve in said last-named pipe, a vertically-depending baffle in an upper portion of said lower cylinder, said baffle lying in a plane between the planes of said separate means.

5. An oil purifier, comprising upper and lower horizontally-disposed cylinders, a substantially vertical partition in said upper cylinder separating the same into a pair of chambers, separate conduits each including a valve connecting said chambers to said lower cylinder, an oil intake pipe connected to one of said chambers, an oil outlet pipe connected to the other of said chambers, a filter in operative association with said outlet pipe for filtering oil entering the same, said filter being in said last-named chamber, a coil in said lower cylinder, said coil including a pipe operatively connected thereto for supplying steam under pressure to said coil, said last-named pipe including a branch pipe leading to said last-named chamber, a valve in said last-named pipe, whereby to selectively supply steam under pressure to said last-named chamber for blowing out the same and said lower cylinder.

6. An oil purifier, comprising upper and lower horizontally-disposed cylinders, a substantially vertical partition in said upper cylinder and separating the same into a pair of chambers, separate means including valves connecting said chambers to said lower cylinders, an oil intake conduit opening into one of said chambers, an oil outlet conduit opening out of the other of

- said chambers, a filter in operative association with said outlet pipe for filtering oil entering the same, said filter being in said last-named chamber, a by-pass pipe connecting said chambers, a valve in said last-named pipe, a coil in said lower cylinder, said coil having connections to a pipe for supplying steam under pressure thereto, said last-named pipe including a branch pipe opening into said lower cylinder.
- 10 7. An oil purifier, comprising upper and lower horizontally-disposed cylinders, a substantially vertical partition in said upper cylinder and separating the same into a pair of chambers, separate means including valves connecting said chambers to said lower cylinder, an oil intake conduit opening into one of said chambers, an oil outlet conduit opening out of the other of said chambers, a filter in operative association with said outlet pipe for filtering oil entering the same, said filter being in said last-named chamber, a by-pass pipe connecting said chambers, a valve in said last-named pipe, a coil in said lower cylinder, said coil having connections to a pipe for supplying steam under pressure thereto, and said last-named pipe including a branch pipe opening into said first-named chamber, said last-named branch pipe having a valve therein.
